COMBINED HOOD AND GRILLE FOR A SELF-PROPELLED FORAGE HARVESTER OR THE LIKE

Joe P. Leinhauser and James L. Vogt, Ottumwa, Iowa,
and James M. Conner, Mamaroneck, and Charles W.
Pelly, Scarsdale, N.Y., assignors to Deere & Company,
Moline, Ill.

Filed Mar. 28, 1972, Ser. No. 238,998

Term of patent 14 years

Int. Cl. D12—09
U.S. Cl. D40—1 E

FIG. 1

FIG. 2

FIG. 3

FIG. 4

FIG. 5

FIG. 6

FIG. 1 is a left side elevational view of a combined hood and grille for a self-propelled forage harvester or the like showing our new design.

FIG. 2 is a right side elevational view thereof.

FIG. 3 is a top plan view.

FIG. 4 is a perspective view as seen from the left rear.

FIG. 5 is a perspective view as seen from the right rear.

FIG. 6 is a rear elevational view.

We claim:

The ornamental design for a combined hood and grille for a self-propelled forage harvester or the like, substantially as shown.
